UNITED STATES PATENT OFFICE.

ALBERT STEFFIN, OF NEW BEDFORD, MASSACHUSETTS, ASSIGNOR TO THE PAIRPOINT CORPORATION, OF NEW BEDFORD, MASSACHUSETTS.

DESIGN FOR A CANDLESTICK.

SPECIFICATION forming part of Design No. 36,875, dated April 12, 1904.

Application filed March 2, 1904. Serial No. 196,249. Term of patent 7 years.

To all whom it may concern:

Be it known that I, ALBERT STEFFIN, a citizen of the United States, residing at New Bedford, in the county of Bristol and State of Massachusetts, have invented a new, original, and ornamental Design for a Candlestick, of which the following is a specification, reference being had to the accompanying drawings, forming part thereof.

In the accompanying drawings, Figure 1 is an elevation of a candlestick having my or-

namental design. Fig. 2 is a plan of the same, the shaft of the candlestick being shown in section.

What I claim as new, and desire to secure by Letters Patent, is—

The ornamental design for a candlestick, as shown.

ALBERT STEFFIN.
